**COVER HOUSING AND HANDLE ASSEMBLY FOR
A FOOD MIXING MACHINE**

David A. Meeker and Charles M. Allen, Troy, Ohio, as-
signors to The Hobart Manufacturing Company, Troy,
Ohio, a corporation of Ohio

Filed Jan. 7, 1960, Ser. No. 58,950

Term of patent 14 years

(Cl. D44—1)

FIG-1

FIG-3

FIG-4

FIG-2

Fig. 1 is a side elevational view of a cover housing and handle assembly for a food mixing machine showing our new design;

Fig. 2 is a top plan view;

Fig. 3 is a rear elevational view; and

Fig. 4 is a front elevational view.

The broken line showing of a lower casing and frag-
mentary portions of a beater shaft in Fig. 1 is for illus-
trative purposes.

We claim:

The ornamental design for a cover housing and handle assembly for a food mixing machine, as shown and described.
